UNITED STATES PATENT OFFICE.

LEONARD F. TARBELL, OF WESLEY, NEW YORK, ASSIGNOR OF ONE-THIRD
TO MERRITT EARL, OF WESLEY, NEW YORK.

WIRE-TIGHTENER.

SPECIFICATION forming part of Letters Patent No. 689,333, dated December 17, 1901.

Application filed July 1, 1901. Serial No. 66,628. (No model.)

To all whom it may concern:

Be it known that I, LEONARD F. TARBELL, a citizen of the United States, residing at Wesley, in the county of Cattaraugus and State of 5 New York, have invented a certain new and useful Improved Wire-Tightener, of which the following is a specification.

This invention relates to an improved wire-tightener adapted to be used in constructing 10 wire fences, the tightener being operatively arranged relatively to a firmly-seated post and connected to the wire so that movement of the tightener will tighten or stretch the wire.

15 The object of the invention is to provide a simple, cheap, and easily-operated device of the above character, all of which will be fully and clearly hereinafter described and claimed, reference being had to the accompanying 20 drawings, in which a preferred adaptation of the invention is shown.

Figure 1 represents a top plan view of a portion of a fence, showing the improved tightener connected to a wire and post and in 25 position to tighten the wire. Fig. 2 represents a top plan view of a portion of a fence, showing the improved tightener connected to a post and wire and in tightening position. Fig. 3 is a side elevation of the improved wire-tightener. Fig. 4 is a detached side view of 30 the body portion of the gripping member with the gripping-blocks in section. Fig. 5 is a detached end view of the body portion of the gripping member. Fig. 6 is a detached bottom view of the lever member. Fig. 7 is a detached 35 top view of the body of the gripping member. Fig. 8 is a detached bottom view of the body of the gripping member. Fig. 9 is a detached view of the bifurcated cam-lever. Fig. 10 is a detached view of the body 40 of the gripping member, looking in the direction of the arrow X, Fig. 4.

In referring to the drawings for the details of construction like numerals designate like 45 parts.

The invention comprises two members, one of which is adapted to be operatively attached to a fence-post and has an operating-handle, which I term the "lever member," and the 50 other member has pivotal support from the lever member and means for gripping the

wire, which I term the "gripping member." The lever member is preferably cast in one integral piece and has a handle 1 at one end, formed so as to be conveniently grasped by 5; the hand of the operator. A slot 2 extends longitudinally through the opposite end of the lever member and terminates at or near the middle of said lever member, and the bifurcations or forks 3, formed by said slot, are 60 spread from each other at their ends, substantially as shown in Fig. 6; and are also bent or offset, as shown in Fig. 3. The object in spreading the ends is to provide for attachment to the fence-post at two separated points, and thereby prevent any twisting or turning movement when operating the device. The extreme ends of the forked portions 3 are sharpened, so that they may embed themselves in a fence-post, substantially 70 as shown in Figs. 1 and 2. The offset or angular end will partially fit around a small post, in which it is not practical to embed the points, and thereby support the tightener in position. The forked portions or bifurcations 3 are connected at their spread extremes by a curved bridge 4, substantially as shown in Fig. 6, and the lever is provided with longitudinal flanges or ribs 5 to strengthen the same. 80

The gripping member preferably consists of a straight flat bar 6, having a deflecting and guiding block 7, a gripping-block 8, a segment 9, provided with a series of perforations 10, and a gripping-lever 11, having a bifurcated end 12, the two parts of which are cams or eccentrics in form and are adapted to operate with the gripping-block 8. The gripping-lever is pivoted to the bar 6 by a pin 13, with the cams 12 in proximity to the gripping-block, as shown in Fig. 3. A set of the guiding and gripping blocks 7 and 8 are located on each side of the bar 6, substantially as shown in Figs. 5, 7, and 8, and as one of the cams 12 operates on each side the device is reversible and can be arranged with either side up with equal facility. The guiding-blocks 7 are located at the ends of the bar on opposite sides thereof and are provided with a curved inner edge 14, substantially as shown 90 in Fig. 4, and the gripping-blocks 8 are located on opposite sides near the side edge and 100

are each provided with an inner serrated or roughened curved surface 15. Each of the blocks 7 and 8 is provided with upper outwardly-extending flanges 16 and 17, which 5 serve to retain the wire in place, the blocks 7 having the flanges 16 and the blocks 8 the flanges 17, and the adjacent ends of the opposed blocks are separated to leave a space 18 (shown in Figs. 3 and 4) for the passage 10 of the fence-wire 19, substantially as shown in Fig. 4. The edges 20 of the cams or eccentrics 12 are serrated or roughened.

The gripping member is detachably pivoted to the lever member by a pin 21, which 15 can be placed in any one of several openings 22 in the lever member and the proper registering opening of several openings 23 in the bar 6 of the gripping member.

A locking-pin 24 is fastened to the lever 20 member by a flexible connection 25, such as a strip of leather, and is adapted to be placed in any one of the perforations 10 in the segment 9, substantially as shown in Fig. 3.

In operation the wire to be tightened is 25 firmly gripped between the gripping-block and the proper cam or eccentric, the points of the lever member are embedded in the fence-post, as shown in Fig. 1, and the lever is turned from the position shown in Fig. 1 30 to the position shown in Fig. 2, thereby tightening the wire and also moving it against the post, so that the fasteners, such as staples 26, can be easily driven over the wire into the post, as shown in Fig. 2.

35 It will be noticed by referring to Fig. 4 that the wire bends slightly in passing between the guiding and gripping blocks. This affords sufficient friction to materially retard the passage of the wire when the cam-lever 40 is loosened and provides a means whereby the wire can be appreciably slackened when desired.

One of the chief advantages of this tightener is that the wire can be tightened and 45 then fastened in place by one man alone, as the device when in the tightening position (shown in Fig. 2) is retained in place by the locking-pin 24, which is inserted in the desired perforation 10, thereby securing the 50 gripping member against pivotal movement with respect to the lever member in a direction to slacken the wire, so that the operator can leave the tightener and drive the necessary staple 26 over the wire.

55 When the tightener is in the position shown in Fig. 2, the corner 27 of the end of the straight bar 6 rests or abuts against the fence-post, as shown, and as the gripping member is fastened to the lever member, as before 60 described, the tension of the stretched wire

tends to draw the contacting and embedded parts of the members more firmly against and into the fence-post instead of pulling the tightener from its position, thereby securely holding it in its tightening position. 65

I claim as my invention—

1. In a wire-tightener, a lever member, a gripping member having guiding and gripping blocks on each side and each set of blocks being adapted to have the wire pass 70 between them and a bifurcated cam-lever adapted to grip the wire against the gripping-block of the set between which it passes, substantially as set forth.

2. A wire-tightener comprising a lever mem- 75 ber having a slotted portion; the bifurcations formed by the slot being spread at their ends and provided with sharpened extremes adapted to embed themselves in a fence-post and connected by a bridge and a gripping mem- 80 ber having pivotal support in the slotted portion.

3. A wire-tightener comprising a lever mem- 85 ber having a bifurcated portion provided with an offset end having sharpened extremes and 90 a bridge connecting the bifurcations, and a gripping member pivoted between the bifurcations and having a straight bar provided with gripping-blocks, a curved perforated segment and a cam-gripping lever, substan- 95 tially as described.

4. In a wire-tightener, a lever member, and a pivotal gripping member having a guiding-block and a gripping-block on each side thereof and a lever having gripping means co- 95 operating with both gripping-blocks.

5. In a wire-tightener, a lever member and a gripping member having an end and a side block arranged on each side thereof, and a lever having a gripping-cam adapted to grip 100 the wire against one of either set of blocks, substantially as set forth.

6. In a wire-tightener, a lever member hav- 105 ing a slotted portion, a gripping member piv- 110 otted in the slotted portion and having a set of guiding and gripping blocks on each side, and a gripping-lever having a bifurcated cam end; the cam parts formed by the bifurcations being adapted to operate against the gripping-block of both sets, substantially as 110 set forth.

7. In a wire-tightener, a lever member, a pivotal gripping member having a segment provided with a plurality of perforations and a locking-pin adapted to be placed in any one 115 of said perforations, substantially as set forth.

LEONARD F. TARRELL.
